UNITED STATES PATENT OFFICE.

Milos Ostoic, of CLEVELAND, OHIO.

AWNINg-SUPPORT.

1,159,986.

Specification of Letters Patent.

Patented Nov. 9, 1915.

Application filed August 17, 1914. Serial No. 857,078.

To all whom it may concern:

Be it known that I, Milos Ostoic, a citizen of the United States, and resident of Cleveland, in the county of Cuyahoga and State of Ohio, have invented certain new and useful Improvements in Awning-Supports, of which I hereby declare the following to be a full, clear, and exact description, such as will enable others skilled in the art 10 to which it appertains to make and use the same.

The objects of the invention are to provide a simple and efficient form of support for the portion of an awning roll intermediate of its extremities and which is so constructed and arranged that it will not wear the awning while assisting in gathering it into a tight roll upon its roller.

Hitherto a supporting device for the central portions of an awning roller has been employed in which the roller and awning thereon has been substantially inclosed within a series of rollers, which supported the weight and prevented them from sagging, but soon injured the awning by the friction it caused so that the awning required frequent repairs and renewals.

To avoid these difficulties the present invention comprises a spool or series of spools 30 supported upon a rotatable rod above the awning roller and intermediate of the ends thereof, and upon these spools are wound bands of heavy canvas, preferably reinforced with metal wire, or other flexible material, the outer ends of which are attached to and wound in turn about the roller, and spool. Means are also provided for rotating the spool and awning roller at equal degrees of speed and in opposite directions so 40 that as the roller winds up the awning the supporting band will unwind from the spool and will be wound upon the roller interposed between the windings of the awning.

The invention is further hereinafter described, shown in the accompanying drawings and specifically pointed out in the claim.

In the accompanying drawings Figure 1 50 is a perspective view of an awning showing the supporting device for the portions of the roller intermediate of its ends; Fig. 2 is a front elevation of the supporting device;

Fig. 3 is a transverse section of one of the spools and awning roller showing the supporting band for said roller. 55

In these views A is an awning roller, mounted in bearings A' A', at the outer extremities thereof and operated in the usual manner by means of a vertical rod B and bevel gears C and D respectively. To support the long roller A a parallel rod E is rotatably mounted in bearings just above the roller A and upon this rod are secured the spools F, F, or a single spool if the roller A is not too long. If only one spool is employed it should be positioned centrally of the ends of the rod E. To each spool is attached one end of a band G of flexible material, preferably of canvas reinforced with copper wire, and the other end of the flexible band is attached to the awning roller A. The band is wound up with the canvas awning upon the roller and supports the roller and awning, and when wound 70 with the awning will unwind from the spool and vice versa, and thus always serves as a support to prevent the roller from sagging and also presents no rubbing corners, and produces no friction which could wear the 80 awning. In this manner the durability of the awning is greatly increased and is limited only by the durability of the entire awning. 75

It will be evident that the band is attached to the awning rod when the awning is unfolded and it will be understood that at this time the band is wound very tightly on the upper rod so that it serves to support the awning rod. When, however, the parts 90 are turned so as to begin to wind up the awning, the band immediately begins to slacken because the diameter of the band roll is greater than the diameter of the awning rod. When, however, the awning is 95 nearly wound up this slack will be taken up because the roll on the awning rod is then of greater diameter than the roll on the upper rod. Consequently, the awning will be rolled in with the band very tightly 100 when the awning is wound up as far as it goes and the band will again be under tension so as to support the awning rod. The rod and spools are rotated by means of an additional bevel gear H which has the same 105 number of teeth as the gear C and engages

the large gear D upon the awning roller and also rotates in the opposite direction therefrom. The spools must be of the same diameter as the roller.

5 This construction provides a simple, efficient and durable improvement which can be quickly attached to any awning. It also greatly diminishes the amount of force required to rotate the awning roller and when 10 several spools and bands are employed it applies the force necessary to rotate the roller at frequent intervals.

The great advantages of this device are that it can be applied to any awning roller 15 of any size or diameter the only consideration being that the spool or spools must be of the same diameter as the roller.

Copies of this patent may be obtained for five cents each, by addressing the "Commissioner of Patents, Washington, D. C."

Having described the invention, what I claim as new and desire to secure by Letters Patent is:

The combination with an awning and roller therefor, of a rotatable member positioned above the same, a flexible band, one end of which is attached to said flexible member, the other end to said roller, and means for rotating said roller and rotatable member in opposite directions.

In testimony whereof, I hereunto set my hand this 29th day of July, 1914.

Milos Ostovic.

In presence of—

Wm. M. Monroe,
P. Buchwald.
